RICHARD T. SCHRIER, GUSS GEORGE, AND WILLIAM H. MEACHAM, OF ALTON PARK, TENNESSEE.

PNEUMATIC VALVE MECHANISM.

1,233,923.

Specification of Letters Patent.

Patented July 17, 1917.

Application filed December 13, 1915. Serial No. 66,599.

To all whom it may concern:

Be it known that we, RICHARD T. SCHRIER, GUSS GEORGE, and WILLIAM H. MEACHAM, citizens of the United States, residing at Alton Park, in the county of Hamilton and State of Tennessee, have invented new and useful Improvements in Pneumatic Valve Mechanism, of which the following is a specification.

This invention relates to a valve mechanism especially designed for use in connection with glass blowing apparatus for supplying air under pressure to the glass blowing devices, but which may be employed for other purposes, the object of the invention being to provide a valve mechanism whereby air under pressure may be alternately supplied to two working parts or elements, and alternately exhausted therefrom.

A further object of the invention is to provide a valve mechanism which when supplying air to one working element will exhaust the air from the other working element, and which is simple, reliable and efficient in action, and capable of being constructed and installed at a comparatively low cost.

The invention consists of the features of construction, combination and arrangement of parts hereinafter fully described and claimed, reference being had to the accompanying drawings in which:

Figure 1 is a vertical section through the valve mechanism, showing the valve in one of its working positions.

Fig. 2 is a similar view showing the valve in its other working position.

In carrying the invention into practice, we provide a valve mechanism comprising an admission chamber or cylinder 67, a distributing chamber or cylinder 68 and an intermediate exhaust chamber 69. The chamber 67 is provided at its lower end with an inlet port 70 connected with a primary feed pipe 67' and has arranged therein a controlling valve 72 governing a feed passage leading to a supply port 73, which valve is adapted to be opened and closed by means of a screw stem 74. The port 73 is connected by a duct 75 with upper and lower feed ports 76 and 77 communicating with the interior of the chamber 68 immediately above and below the horizontal transverse center thereof, which chamber 68 is provided with upper and lower discharge ports 78

and 79 connected by pipes or conductors 80 and 81 leading to the elements, not shown, which are to be supplied with air.

The chamber 68 has arranged therein a governing valve 82 of the sliding piston type which is provided with a downwardly and exteriorly projecting stem 83, and this valve 82 controls the ports 76 and 77 and also controls upper and lower exhaust ports 84 and 85 extending laterally between the chamber 68 and the exhaust chamber 69, which is provided with a final exhaust port 86. Arranged within the chamber 69 is an exhaust valve 87 of the piston type and having a cut-off sleeve 88 depending from its head portion and exhaust ports 89 in its head portion, said valve being provided with a downwardly and exteriorly projecting stem 90, the respective valve stems 83 and 90 being slidably and pivotally connected with the opposite arms of a centrally fulcrumed valve actuating lever 91, whereby said valves are adapted to be simultaneously and alternately moved in opposite directions. The stem 83 is also connected with a valve controlling lever 92 movable upwardly and downwardly whereby the valves 82 and 87 will be adjusted to upper and lower feed positions and lower and upper exhaust positions, respectively. Thus when the lever 92 is elevated to the position shown in Fig. 1, the valve 82 will be in position to close the port 76 and open the port 77 for the flow of air through the pipe 81, and for the exhaust of air to the atmosphere through the ports 84 and 86, while when the lever 92 is depressed, as shown in Fig. 2, it will move valve 82 in a direction to close the port 77 and open the port 76, while the valve 87 will be moved to close the port 84 and establish communication between the port 85 and the ports 86 and 89 for the exhaust of air from the pipe 81.

It will thus be seen that the invention provides a valve mechanism whereby compressed air from a suitable source may be supplied alternately to two working elements, and exhausted from each working element in turn while the other is being supplied with air, whereby said elements may be alternately operated. While the invention is primarily designed for use in connection with the working devices of a glass blowing apparatus, it will also be seen that it is adapted for use in connection with any

type of apparatus for supplying and exhausting air to and from working parts in the manner described. It is to be understood, of course, that the valve actuating device or lever 92 may be operated in any suitable manner.

We claim:—

1. A valve mechanism for controlling the supply of air to pneumatically operated elements comprising an actuating device, admission, distributing and exhaust chambers, said admission chamber having inlet and feed ports, said distributing chamber having sets of inlet, feed and exhaust ports, and said exhaust chamber having an exhaust port and communicating with the exhaust ports of the distributing chamber, piston valves operating in the distributing and exhaust chambers and controlling the respective ports, a connection between said piston valves for operating the same in reverse directions in unison, and a controlling connection between one of said pistons and the actuating device.
2. A valve mechanism for controlling the supply of air to pneumatically operated elements comprising a valve controlled admission chamber, a distributing chamber having upper and lower air inlet and discharge ports, an exhaust chamber having an outlet port and exhaust ports connecting said

chamber with the upper and lower portions of the distributing chamber, a piston valve controlling the inlet ports in the distributing chamber, an exhaust valve controlling the ports in the exhaust chamber, and means for simultaneously operating said valves in opposite directions.

3. A valve mechanism for controlling the supply of air to pneumatically operated elements comprising an actuating device, a valve controlled admission chamber, a distributing chamber having upper and lower air inlet and discharge ports, an exhaust chamber having an outlet port and exhaust ports connecting said chamber with the upper and lower portions of the distributing chamber, a piston valve controlling the inlet ports in the distributing chamber, an exhaust valve controlling the ports in the exhaust chamber, a lever pivotally connecting said valves for movement in opposite directions, and means for communicating motion to said lever from said actuating device.

In testimony whereof we affix our signatures in presence of two witnesses.
